W. F. MENK

ROUTE INDICATOR

Filed Aug. 21, 1925

Inventor

William F. Mink

By Jack Snyder
Attorney

UNITED STATES PATENT OFFICE.

WILLIAM F. MENK, OF PITTSBURGH, PENNSYLVANIA.

ROUTE INDICATOR.

Application filed August 21, 1925. Serial No. 51,570.

This invention relates to an automobile route indicator of a type somewhat similar to the device disclosed in my pending United States patent application, bearing Serial No. 5 48,120, filed August 4th, 1925, and besides embodying the objects of the latter has for its further object to provide a more efficient and simplified instrument by which an automobile driver may ascertain at a glance his 10 exact position on the route over which he is traveling.

To the accomplishment of these and such other objects as may hereinafter appear the invention consists of the novel construction, 15 combination and arrangement of parts hereinafter described and claimed, it being understood that changes in the form, proportions and minor details of construction may be resorted to which come within the scope 20 of the claims hereunto appended.

In the drawing forming a portion of this specification, and wherein like numerals of reference designate corresponding parts throughout the several views:—

25 Figure 1 is a front elevation of a route indicator.

Figure 2 is a similar view with the door removed therefrom.

30 Figure 3 is a side view of the device with the casing shown in section.

Figure 4 is a top plan view of the driving gear and associated parts.

Figure 5 is a side view of one of the spool supports.

35 Figure 6 is a side view of the spool.

Figure 7 is a diagrammatic view of the wiring arrangement for operating my improved indicator.

Referring in detail to the drawing 1 de- 40 notes a cylindrical casing provided with a peripheral flange 2 by which the indicator is adapted to be attached to the instrument board of an automobile. The casing is open at its front and provided with a door 3 hingedly connected thereto, as indicated at 4.

A pair of spaced parallel, extending spool supports 5, 6 are permanently fixed to the side wall of the casing 1. A carrier spool 7 is fixed on the shaft 8 which latter is journaled for rotation in the apertures 9 formed in respective supports 5 and 6, adjacent to the upper ends thereof. A feeder spool 10 is fixed on the shaft 11 which latter is journaled for rotation in the apertures 12 formed in respective supports 5 and 6 adjacent to the

lower ends thereof. The aperture 12 in the support 6 is elongated for the purpose to be described.

Each of the supports 5 and 6 is formed with a forwardly projecting centrally disposed apertured arm 13 which carries a slide bar 14 attached thereto by means of the screws 15.

The web 16 provided with indicating data as indicated at 17, is rolled from the carrier spool 7, passes over the slide bar 14 and is wound on the feeder spool during the operation of the device. One marginal edge of the web 16 is calibrated in mile units as shown at 18, and the other marginal edge is formed with slots 19, one of which is aligned with an associated indicating data 17. It will be noted that while the edge 18 of the web 16 is calibrated in mile units, the same may be calibrated in fractions of miles if desired.

The position of each line of indicating data 17 and its associated slot 19 is determined by calculating the movement of the web 16 relatively to the distance of travel of the motor vehicle and each route requires a special web arranged for the particular route. When starting on a route the web 16, therefor is wound on the carrier spool 7 and the free end attached to the feeder spool 10 by clamping the said free end under the resilient holder 20 with which each of the spools is provided. The web 16 is then adjusted until the pointer 21, carried by the arm 13 of the support 6, is set at "zero" of the mile calibrations 18. Adjustment of the web 16 is also required in the event that the vehicle starts on the route at a known distance from the starting point of the route for which the web is intended, or if for any reason, a departure from the regular route is taken.

An adjusting gear 22 is fixed to one end of the shaft 8, and an adjusting gear 23 is fixed to the corresponding end of the shaft 11. An intermediate gear 24, rotatably mounted on the support 5, is in mesh with the adjusting gears 22 and 23. A bevel gear 25 is fixed to one face of the intermediate gear 24 and meshes with a bevel gear 26 fixed adjacent to the lower end of the adjusting rod 27. The latter is suitably journaled for rotation and is provided with a knurled head 28 to facilitate the adjusting operation. The head 28 projects through an aperture 29' provided therefor in the door 3. By turning the rod 27 in the clockwise direction the spools 7

and 10 will be rotated in the same direction to unwind the web 16 from the carrier spool 7 and wind same on the feeder spool 10. By turning the rod 27 in the counter clockwise direction the rotation of the spools 7 and 10 is reversed and the web will unwind from the feeder spool 10 and wind on the carrier spool 7. This arrangement will facilitate the adjustment of the web 16 to bring the desired mile unit into registration with the pointer 21 for the purpose hereinbefore stated.

A gear 29 is fixed to the shaft 11 on the end thereof remote from the end carrying the gear 23. The gear 29 is in mesh with the spiral 30 carried on the front face of the worm gear 31. The latter is journaled for rotation on the casing back 32, as indicated at 33, and is in mesh with the worm 34, fixed on the drive shaft 35. The drive shaft 35 is operatively connected to some part of the vehicle mechanism that provides uniformly regular or intermittent movement only while the vehicle is in motion, preferably the speedometer shaft.

When adjusting the web 16, as herein stated, it is necessary to disengage the gear 29 from the spiral 30. This is accomplished by pulling the stop rod 36 forwardly. The rod 36 is rotatably connected to the link 37 which latter is rotatably mounted on the shaft 11. The rod 36 extends through a key hole slot 38 formed in the laterally disposed bracket 39 formed integral with the support 6. The rod 36 is provided with a laterally disposed pin 39' which is adapted to pass through the slot 38 and seat on top of the bracket 39 for holding the gear 29 disengaged from the spiral 30, thereby maintaining the device in the inoperative position if for any reason desired, and permitting of the adjustment of the web 16 in the manner described. The rod 36 is formed with a knurled head 36^a to facilitate its operation and the latter projects through an opening 36^b in the door 3 to allow the manipulation thereof when the latter is in the closed position. A spring 36^c is mounted on the rod 36 between the bracket 39 and the link 37 for maintaining the gear 29 in mesh with the spiral 30 when the rod 36 is released.

A substantially U-shaped resilient tension member 40 is pivotally connected, as at 41, to the upper end of the side wall of the casing 1. The connection 41, is provided with a spring 42, which acts to press the ends of the arms 43 and 44 against opposite sides of the outer face of the web 16 as the latter is traveling over the slide bar 14, for the purpose of tensioning the web 16 during its operation. The tension member 40 is insulated from the casing 1 by the insulation 45, and the arm 43 further serves as a contact element for contacting with the slide bar

14 when any of the slots 19 of the web 16, pass thereunder during the operation of the device for the purpose to be described.

The door 3 is formed with a centrally disposed elongated observation slot 46 which is disposed directly over the slide bar 14. The indicating data 17 passing over the slide bar 14 may be distinctly read through the slot 46.

A lamp 47 is mounted in the casing 1 and projects through an aperture provided therefor in the door 3. The latter carries a reflector 48 for deflecting the light from the lamp 47 over the data 17 showing in the slot 46.

A buzzer 49 or some other sound producing device is fixed to the casing and is disposed in rear of an aperture 50 formed in the door 3 to amplify the sound of the buzzer 49.

The tension member 40 is connected with the lamp 47 by the conductor 51, the lamp 47 is connected to the buzzer 49 by the conductor 52, and the buzzer 49 is connected with the battery 53 by the conductor 54, as clearly shown in Figure 7, of the drawing. By this wiring arrangement, the buzzer 49 and lamp 47 will function simultaneously each time that the arm 43, of the tension member 40 contacts with the slide bar 14 through any of the web slots 19.

In practice the operation of my improved indicator is as follows:—The stop rod 36 is first pulled forwardly disengaging the gear 29 from the spiral 30. The web 16, provided with the indicating data 17 of the route desired, is wound on the carrier spool 7 by rotating the adjusting rod 27 in the counter clockwise direction. As the tension member 40 is pivoted to the casing 1 it can be shifted so as not to impede the winding of the web upon the spool 7.

When the entire web 16 has been wound on the spool 7, the free end thereof is positioned over the slide bar 14 and attached to the feeder spool 10. By rotating the adjusting rod 27 in the clockwise direction the web 16 may be wound upon the spool 10 until the mile unit 18 on the web 16 registers with the pointer 21. The stop rod 36 is now released causing the gear 29 to mesh with the spiral 30.

Upon movement of the motor vehicle, the worm 34 being attached to the speedometer shaft by the shaft 35, will drive the worm wheel 32 thereby rotating the feeder spool 10, as the latter is fixed on the same shaft 11 as the gear 29 in mesh with the spiral 30 of the wheel 32. The operation of the drive gearing is such that during the operation of the device, the web 16 will unwind from the carrier spool 7 and wind upon the feeder spool 10.

Assuming that at a distance of thirty five miles from the starting point there is a rail road crossing on the route, the web 16 will

have been so constructed that when the mile unit 18, designating thirty five miles registers with the pointer 21 and with the elongated door slot 46, the arm 43, of the tension member 40, will contact with the slide bar 14 through the web slot 19, associated with the indicating data 17, namely "R. R. Crossing". While the arm 43 is contacting with the bar 14, the operating circuit is closed, thereby simultaneously operating the 10 buzzer 49 and lamp 47. In this manner all the information provided by the indicating data 17 will be brought to the attention of the driver at the exact place and time that 15 they are encountered on the route.

What I claim is:

1. A route indicator comprising a casing including a hinged door formed with an observation slot, a horizontally adjustable 20 feeder spool, a web carrying spool, supporting means common to said spools and secured within the casing, a slide bar arranged between said spools, positioned parallel to said slot and mounted in said means, a shiftable web wound on the carrier spool, windable on the feeder spool, sliding against said bar between it and the slot and having spaced route indications for successive exposure through said slot, a spring controlled tensioning element operating against the outer 25 face of the web and pivotally connected to the casing, means operating on an axis at right angles to the axis of the feeder spool for driving the latter when it is in an inward position, horizontally adjustable means for shifting said feeder spool inwardly and outwardly and means for revolving said spools when the feeder spool is shifted outwardly.
2. A route indicator comprising a casing

formed with an observation slot, feeder and carrying spools supported within the casing, a slide bar positioned between the spools and arranged in a normally open circuit, a shiftable web winding off the carrier spool and 45 windable on the feeder spool extending across said slot and slideable over said bar, said web having spaced route indicating indicia for successive exposure through said slot and further having one side thereof formed with 50 spaced apertures, audible and visible signals carried by said casing and in said circuit, and an insulated spring controlled pivoted U-shaped member in said circuit, having its arms bearing against opposite sides of the 55 outer face of the web for tensioning it and further having one of its arms operating through said apertures to contact with the slide bar to close the circuit to provide for the activity of the signals.

3. A route indicator comprising a casing having an observation slot, a shiftable web extending across and having spaced route indicating indicia for successive exposure through said slot, said web further having 65 spaced apertures at one side thereof, shifting means for the web, a slide bar in a normally open circuit and over which passes said web, audible and visible signals in said circuit, and a spring controlled, pivoted insulated element in said circuit, bearing against the outer face of said web for tensioning it, positioned within said casing and having a part thereof operating through said 70 apertures to engage said bar to close said 75 circuit thereby providing for the activity of said signals.

In testimony whereof I affix my signature.

WILLIAM F. MENK.
